UNITED STATES PATENT OFFICE.

WILLIAM M. GRUNER AND WILLIAM C. FINK, OF SPRINGDALE,
PENNSYLVANIA.

SAFETY TROLLEY-ALARM.

SPECIFICATION forming part of Letters Patent No. 743,272, dated November 3, 1903.

Application filed September 14, 1903. Serial No. 173,100. (No model.)

To all whom it may concern:

Be it known that we, WILLIAM M. GRUNER and WILLIAM C. FINK, citizens of the United States, residing at Springdale, in the county 5 of Allegheny and State of Pennsylvania, have invented a new and Improved Safety Trolley-Alarm, of which the following is a specification.

Our invention relates to safety trolley-
10 alarms, an alarm on the car adapted to be
sounded upon jumping of the trolley from
the conductor-wire or breaking of the trolley-
sheave through special devices or instrumen-
talities employing a local circuit with a spe-
15 cial circuit-closer, the circuit-closer being
adapted in its operation to simultaneously
through a special subtrolley complete or re-
store the motor-circuit from the conductor-
wire down through the car to ground or
20 through metallic return, as will be under-
stood.

The invention consists in the special con-
struction, combination, and arrangement of
25 devices and instrumentalities shown in the
accompanying drawings, which will hereinaf-
ter be fully described.

The features of novelty in our invention
will be pointed out in the claims.

In the drawings, Figure 1 is a view illus-
30 trating our invention in use. Fig. 2 is an
enlarged detail view showing the main and
subtrolleys in normal working position. Fig.
3 is a similar view with the main trolley-head
removed, showing the subtrolley in use; and
35 Fig. 4 is a detail view looking in the direc-
tion of the arrow, showing the main and sub-
trolley heads in normal position.

In the embodiment of our invention we em-
ploy, with the ordinary trolley of a motor-car,
40 a subtrolley normally out of action, a local
bell-circuit on the car, and special means op-
erating to close the local bell-circuit and si-
multaneously recomplete the motor-circuit
upon impairment of the main-trolley sheave
45 or jumping thereof from the conductor-wire.

In the drawings, A denotes any type of mo-
tor-car carrying wires B, bells C, and any suit-
able source of energy D.

The main-trolley pole E is provided with
50 any suitable head F, adapted for ready de-
tachment, carrying the collector-sheave G.

H denotes a subtrolley-pole, having at its
upper end any suitable device adapted to
catch the conductor-wire upon impairment
of the main collector-sheave G or jumping 55
action thereof from the conductor-wire. In
our drawings we have shown one form of catch-
ing device, consisting of an elongated grooved
roller I, which is normally out of contact with
the conductor-wire. It will be noticed that 60
when the main collector-sheave G is in posi-
tion against the conductor-wire the roller I is
supported by its arm H free of the conductor-
wire, but in position with the side edges I' of
its groove in line or slightly above the con- 65
ductor-wire. The subtrolley-pole H has piv-
otal connection with any suitable bracket J,
secured to the main-trolley pole E, and is
yieldingly supported by means of an arm K,
pivoted thereto at K'. The arm K extends 70
through an opening or suitable keeper in the
main-trolley pole and has a spring L thereon,
arranged between any suitable head L' and
the pole E, as shown. A suitable sleeve or 75
collar M is arranged on the arm K between
the poles E and H. This sleeve or collar is
designed to preserve the relative normal po-
sition of the collecting-sheave G when in con-
tact with the conductor-wire and the catch
device or roller I when out of collecting con- 80
tact, but in position with its side edges I' sup-
ported in line or slightly above the conductor-wire,
thereby insuring its proper working
or catching the conductor-wire upon impair- 85
ment of the sheave G. The lower end of the
subtrolley-arm H below its pivotal connec-
tion is provided with a double contact N,
consisting of a projecting conducting-surface O
and an insulated surface P. The conductive 90
surface O when, in closed position with any
suitable contact Q will complete the motor-
circuit from the catch device I when the lat-
ter is against the conductor-wire down the
main-trolley pole. At the same time the in- 95
sulated surface P will force together any suit-
able normally open terminals R of the bell-
circuit.

Our invention will be understood from the
above description. We would have it under-
stood that we do not desire to be limited in 100
its scope to the identical devices shown and
described. We believe it is new with us in

similar inventions to provide means consisting of a subtrolley having at one end any form of device serving to catch the conductor-wire upon jumping action therefrom of 5 the main collector-sheave and with the support of the catching device operating to close a local circuit on the car, whereby an alarm is sounded, the catch-device support being also adapted for simultaneously closing the 10 motor-circuit from the conductor-wire to and through the motor on the car.

According to our invention the subtrolley is so arranged that the moment the collector or regular trolley leaves the conductor-wire 15 it will immediately come into action, restoring the motor-circuit, and thereby preventing the car from getting beyond control of the operator. It will be noticed that an alarm is sounded at both ends of the car, notifying the motorman and conductor that they 20 are not running on the main or collector trolley, whereby they can at their early convenience stop the car and readjust or remove the main trolley if its sheave or head be broken. 25 The yielding support for the subtrolley makes it as substantial as the main trolley.

Having thus described our invention, what we claim as new, and desire to secure by Letters Patent, is--

30 1. The combination with the main trolley of a motor-car, of a conductor-wire-catching device carried by the main-trolley support, a local alarm-circuit on the car, and means operating, upon contact of the said catching device, with the conductor-wire, to restore the 35 motor-circuit and simultaneously close the

said local alarm-circuit, substantially as described.

2. The combination with the main trolley of a motor-car, of a subtrolley, an alarm-circuit on the car, means on the main trolley consisting of two circuit-closers, one thereof in the motor-circuit and the other in the alarm-circuit, the said circuit-closers being operated upon contact of the subtrolley with the 45 conductor-wire.

3. In combination with a motor-car having main and subtrolley arms, and with the subtrolley yieldingly supported and out of action, of a bell-circuit on the car, and two normally open circuit-closers in operative position with the said subtrolley-arm, whereby, upon yielding action of the said subtrolley, as when in contact with the conductor-wire, both the said circuit-closers will be operated, 50 one completing the motor-circuit and the other the bell-circuit, substantially as described.

4. In combination with a motor-car having main and sub trolleys and a local alarm-circuit on the car, of motor-circuit and alarm- 60 circuit contacts on the main trolley, and a double contact on the subtrolley adapted in operation for closing the motor-circuit and also the said alarm-circuit, the said motor-circuit and alarm-circuit contacts being insulated, substantially as described.

WILLIAM M. GRUNER.
